(57) **CLAIM**

I claim the ornamental design for a moving sculpture, as shown.

DESCRIPTION

FIG. 1 is a front, perspective view of my moving sculpture;

FIG. 2 is a left side elevational view;

FIG. 3 is the front elevational view;

FIG. 4 is a rear elevational view;

FIG. 5 is a right side elevational view;

FIG. 6 is a top plan view; and,

FIG. 7 is a bottom plan view.

The directional arrows on the disks in FIG. 1 are for illustrative purposes only and form no part of the claimed design.
